William Scamis
The Schedule annexed to the above Letters Patent and
making part of the same containing a description in
the name of the said William Scamis himself, of
his improvement being a helping power machine

This machine which is designed to operate any kind of
mechanical machinery, consists of a frame the size
and proportion of which must be varied according to the
machinery to be operated. At the centre of the top of the
frame is an arbor to which is attached a pendulum rod
at or near the end of which is the pendulum weight, in
the arbor, and perpendicular to the pendulum rod are
two arms of levering in opposite directions, each end
operating in a crown or centre wheel, properly fitted
with teeth, and by the alternate action of these wheels
the pendulum is kept in motion. On the other end
of the arbor, arms are also fixed to which the machine
may be operated is attached. When the pendulum is
swung to either extreme its motion is accelerated back
by means of springs operating on the pendulum rod.
The motion to each of the wheels is conducted by means
of arms or other vehicles and pinions from a weight
attached to a ratchet wheel on the machine may be kept
in motion by any other sufficient power. To each of
these crown or centre wheels is a dog to catch in the
teeth of the wheel and suspend its motion while the
other wheel is in operation. The dog is disengaged from
the teeth of the wheel when the pendulum is swung to its
opposite direction by a chain or rod to which
it is attached, the other end of the arbor or rod being
fixed to a pin or bolt of levering levers from the
other end of the wheel thus as they come into use.

and is operating on the even gins, but are contained
within 20 ft. from the road, and when the road is closed
hence the even, having passed beyond its road, the mo-
tion of the wheel is again held in check by the log.
Thus by the alternate action of the wheel, as the mo-
tion communicated to the foundation is continued until
the log has an even draw.
